UNITED STATES PATENT OFFICE.

JOHN BERG, OF CHICAGO, ILLINOIS, ASSIGNOR TO METAL SPECIALTIES MANUFACTURING COMPANY, OF CHICAGO, ILLINOIS, A CORPORATION OF ILLINOIS.

SEALING-STRIP MACHINE.

1,266,197.

Specification of Letters Patent.

Patented May 14, 1918.

Application filed August 31, 1914. Serial No. 859,418.

To all whom it may concern:

Be it known that I, JOHN BERG, a citizen of the United States, residing at Chicago, in the county of Cook and State of Illinois, have invented a new and useful Improvement in Sealing-Strip Machines, of which the following is a specification.

My invention relates particularly to machines adapted to hold a roll or rolls of sealing-strip material, provided with means for moistening the gummed surface of the sealing-strip and with means for severing the sealing-strip.

My primary object is to provide a simple construction and improved operation. The improved machine is well adapted to the purpose of serving a large and heavy sealing-strip as well as smaller and lighter sealing-strips.

20 The invention is illustrated in its preferred embodiment in the accompanying drawings, in which:

Figure 1 represents a side elevational view of a machine embodying my invention, with one of the side frames broken away and a cross member shown in section; Fig. 2, a broken vertical section taken as indicated at line 2 of Fig. 3; Fig. 3, a plan view of the machine; Fig. 4, a broken plan view, partly in section, showing an extensible gage-rod employed; Fig. 5, a section taken as indicated at line 5 of Fig. 1, the view showing also partly in section one of the tension members employed; Fig. 6, a section taken as indicated at line 6 of Fig. 2, and showing a detail of the combination paper guide and cutter employed; Fig. 7, a broken plan view showing a detail of the connection between the water-font and the main frame; 40 and Fig. 8, a broken perspective view illustrating the manner in which the cross members of the frame are connected with the side members.

In the embodiment illustrated, A represents the frame of the machine; B, a paper roll carrying a roll of gummed tape B¹; B², tension plates embracing the roll of gummed paper; C, a guide-roll journaled in the lower central portion of the frame and associated with a shoe or curved guide C¹ which is disposed beneath it; D, a feed-roll journaled in the upper front portion of the frame; E, a moistening roll journaled in a water-font E¹ which is detachably mounted on the front portion of the frame; F, a combination strip

positioning and severing device disposed between the upper portions of the rolls D and E and adjustably connected to vary the arc of contact between the moistening roll and the gummed strip; and G, an extension gage 60 attached to the front portion of the frame at one side thereof.

The frame A, in its preferred construction, comprises side frames 1 which are rigidly connected together at their lower portions by a rear cross-member 2 and a front cross-member 3. Each side-member 1 of the frame has at its rear end a standard 1^a for the support of the paper-roll B. The side members are provided with out-turned flanges or feet 1^b provided with slots adapted to receive screws by means of which the machine may be secured on a table or counter. The side frames are provided on their lower portions with perforations 4 through 75 which extend screw-bolts 5 which engage vertical slots 6 with which the down-turned ends or flanges 7 of the cross-members 2 and 3 are provided. Thus the frame is of knock-down construction, and, while the parts are 80 rigidly fastened together, the frame may be readily taken apart.

The paper-roll B is mounted on a shaft 8 having threaded ends which rest in open sockets or bearings 9 with which the upper 85 ends of the standards 1^a are provided. The threaded ends of the shaft 8 are equipped with knurled nuts 10 which serve to adjust the tension of the plates B² against the sides of the roll of paper B¹, it being noted that 90 the roll B is preferably made somewhat short.

Each member B² preferably comprises a sheet-metal plate which is provided with a vertical slot 11 extending from the lower 95 end of the member to near the top. The slot 11 enables the member B² to slide downwardly with the legs of the member embracing the shaft 8. At the lower end of the slot 11 is an enlarged recess or notch 100 12 which engages the rear cross-member 2 of the frame. Each plate B² is provided with an outwardly-bowed spring 13, the bowed portion of which engages the corresponding nut 10. The spring member 13 is 105 preferably formed by severing the metal of the plate along lines 14 flanking the upper portion of the slot 11, the lower ends of the incisions 14 being intersected by incisions 15 which extend to the slot 11. Thus, the spring 110

member 13 is bifurcated and embraces the shaft 8.

The roll C is a small roll beneath which the gummed strip B¹ is adapted to pass. 5 The shoe C¹ is a sheet-metal member secured to the cross-member 3 and extending rearwardly therefrom, with the rear portion being made concave, as indicated at 16, this conforming approximately to an arc of the roll C, and affording a curved passage for 10 the strip. This curved passage is adapted to turn the end of the strip upwardly when the strip is being threaded into the machine, thus facilitating this operation.

15 The rolls D and E have their axes disposed in a plane a considerable distance above the roller C. The rolls D and E are preferably of the same diameter and are much larger than the roll C. The roll D 20 has the ends of its shaft 17 extending from the side-members 1 of the frame and serving as pivots for arms 18. The arms 18 extend forwardly and upwardly and carry a cross-plate 19 which forms a part of the device F. 25 The arms 18 are preferably formed integral with the cross-member 19. The member 19, as shown in Fig. 6, is struck downwardly between the points where it is supported by the arms 18, thus affording a channel 20 30 through which the gummed strip passes. The upper wall of the channel 20 is formed by a steel plate, or knife, 21 having a serrated sharpened front edge 21^a which is disposed slightly in the rear of the upper portion of the roll E. The knife-plate 21 is secured to the portions of the cross-member 19 by screws 22. The device F is adjustably secured in position by means of a resilient arm, or link, 23, which is provided with 35 forations 24 and 25, either one of which may be brought into locking engagement with a stud or pin 26 with which the front end of one of the side members of the frame is provided.

40 The moistening roll E is provided with trunnions or stub shafts 27 which rest in open recesses or bearings 28 with which the upper edges of the ends of the font E¹ are provided. At or near the rear vertical corners of the font E¹ are provided laterally extending lugs 29 which engage slots or recesses 30 which are provided in the upper edges of forward extensions 31 of the side members of the frame. The extensions 31 45 are offset downwardly somewhat, thus affording vertical shoulders 32 which are engaged by the rear wall of the font. Thus the font is readily demountable, to enable it to be cleansed. The device F normally occupies a position above the rear portion of the font, but is capable of being swung rearwardly and upwardly about the axis of the roller D when the frame or link 23 is disconnected from the stud 26. In this manner, the device F may be retracted or gotten

out of the way to facilitate the removal of the font. It may be added that when the font is in position on the frame, the rear portions of its ends are embraced by the forward extensions 31 of the side-members 70 and 7.

The gage device G comprises a series of telescoping tubular members 33, 34 and 35, and a rod 36 fitting within the smallest tubular member and provided with a laterally turned end 37. The largest tubular member is secured to the front portion of one side member of the frame by a clamping device 38. The outer ends of the tubular members are split or provided with slits 39 and are equipped with clamping-rings 40. Thus, the extension gage may be set so that the laterally-turned member 37 will be at any desired distance in front of the knife 21 85 to serve as a means for measuring the strip which is to be moistened and severed.

In the use of the improved machine, if the gummed surface of the strip is on the outside, the strip may be threaded through the machine in the manner shown by the full lines in Fig. 1, that is, passing from the lower side of the roll B¹ beneath the roll C, thence above the feed-roll D, thence through the device F and across the top of the moistening roll E. If the gummed surface is on the inner side of the strip, the strip may pass from the upper side of the roll B¹, in the manner indicated by the dotted line 41 to the lower side of the roll C, and thence 90 over the roll D and through the device F. As the strip is drawn across the roll E, it is held in contact with said roll throughout the arc 42, as shown in Fig. 1. Where the gummed strip is a heavy one, it is desirable 95 that the arc of contact shall be large in order that the desired moistening effect shall be secured. When the strip is a lighter one, the arc of contact may be varied by adjusting the position of the device F. After the strip has been drawn out and moistened, it 100 may be severed by a quick movement of the arm. Because of the position of the knife 21, it is possible to sever a strip with the greatest facility, even where a long length 105 has been drawn over the moistening roll. After the severing operation, the strip may, by pressing upon the strip and turning the upper portion of the roll D forwardly, be fed through the device F a sufficient distance 110 to enable the end of the strip to be grasped 115 preparatory to moistening a further length of the sealing strip.

The roll E, for sanitary reasons, is preferably of metal. It applies the water to the 120 gummed surface of the strip, but the water is apt to be left on such a surface in the form of beads. Accordingly, it is preferred to provide a small metal distributing roll H 125 over which the strip is drawn as it passes 130

from the moistening roll E. The roll H is demountably supported in bearings H¹ carried by the front portions of the sides of the water-font E¹, and it serves effectually to 5 distribute the water and force its absorption by the mucilage of the strip.

The machine described is simple, durable and easily operated. It is well adapted in 10 every way to its purpose, and may be adjusted to suit varying conditions, depending upon whether a light or heavy sealing strip is employed. The moistening roll and water-font may be readily removed from time to time for cleansing purposes.

15 The foregoing detailed description has been given for clearness of understanding only, and no unnecessary limitation should be understood therefrom, but the appended claims should be construed as broadly as permissible in view of the prior art.

What I regard as new and desire to secure by Letters Patent, is:

1. In a machine of the character set forth, the combination of a frame, a paper-roll 25 mounted therein, a feed-roll mounted at a distance in front of the paper-roll, a water-font mounted in front of said feed-roll, a moistening-roll therein, and means disposed between the upper portions of said feed-roll 30 and moistening-roll adapted to change the arc of contact which exists between the gummed strip and moistening-roll when the strip is being served, said means being provided with a strip severing device.

35 2. In a machine of the character set forth, the combination of a frame, a paper-roll mounted therein, a feed-roll mounted at a distance in front of the paper-roll, a water-font mounted in front of said feed roll, a moistening-roll therein, and pivotally-mounted 40 adjustably secured strip-positioning and severing means disposed between the upper portions of said feed roll and moistening roll.

45 3. In a machine of the character set forth, the combination of a frame, a paper-roll mounted therein, a feed-roll mounted at a distance in front of the paper-roll, a water-font mounted in front of said feed roll, a moistening-roll therein, and a combination 50 strip guide and cutter so disposed in the space between said feed-roll and moistening-roll as to deflect the strip into the space between the upper portions of said feed-roll 55 and moistening-roll.

4. In a machine of the character set forth, the combination of a frame, a paper-roll mounted therein, a feed-roll mounted at a distance in front of the paper-roll, a water- 60 font mounted in front of said feed-roll, a moistening-roll therein, and a strip guide and severing device disposed between the upper portions of said feed-roll and moistening-roll and adapted to bend the strip between said feed roll and moistening-roll and

hold the strip in contact with the moistening-roll throughout a substantial arc of its surface during the operation of serving the strip, said device having a cutting edge disposed close to the moistening-roll.

70

5. In a machine of the character set forth, the combination of a frame, a paper-roll mounted therein, a feed-roll mounted at a distance in front of the paper-roll, a water-font mounted in front of said feed roll, a moistening-roll therein, a movable strip-severing device disposed between the upper portions of the feed-roll and moistening-roll and having a forwardly directed severing edge disposed close to the moistening-roll, and means for adjustably securing said strip-severing device fixedly in position.

75

6. In a machine of the character set forth, the combination of a frame, a paper-roll mounted therein, a feed-roll mounted at a distance in front of the paper-roll, a water-font mounted in front of said feed-roll, a moistening-roll therein, and a strip-positioning and severing device disposed between the upper portions of the feed-roll and moistening-roll and having arms pivotally supported near the axis of the feed-roll, said device adapted to deflect the strip between the upper portions of said feed-roll and moistening-roll.

80

7. In a machine of the character set forth, the combination of a frame, a paper-roll mounted therein, a feed-roll mounted at a distance in front of the paper-roll, a water-font mounted in front of said feed-roll, a moistening-roll therein, a strip positioning and severing device disposed between the upper portions of the feed-roll and moistening-roll and having arms pivotally supported near the axis of the feed-roll, and an arm 101 connected with said device and detachably connected with said frame.

85

8. In a machine of the character set forth, the combination of a frame, a paper-roll mounted therein, a feed-roll mounted at a distance in front of the paper-roll, a water-font mounted in front of said feed roll, a moistening-roll therein, a strip positioning and severing device disposed between the upper portions of the feed-roll and moistening-roll and having arms pivotally supported near the axis of the feed-roll, and an arm connected with said device and detachably and adjustably connected with the frame.

90

9. In a sealing-strip machine, the combination of a frame, a paper-roll mounted therein, a feed-roll mounted at a distance in front of the paper-roll, a water-font demountably carried by the front end of the said frame, a moistening-roll journaled in 125 said font, and a pivotally mounted, detachably held swinging strip positioning and severing device projecting over the font and adapted to be swung away therefrom to permit removal of the font.

130

10. In a sealing-strip machine, the combination of a frame, a paper-roll mounted therein, a feed-roll mounted at a distance in front of the paper-roll, a water-font carried by the front end of said frame, a moistening-roll journaled therein, a withdrawable strip positioning and severing device normally projecting over the rear portion of the font, and disengageable means normally securing said strip positioning and severing means in said projecting position. 30
11. In a sealing-strip machine, the combination of a frame, a paper-roll mounted therein, a guide-roll mounted below and in front of the paper-roll, a concave shoe disposed below said guide-roll, a feed-roll mounted above and in front of said guide-roll, a water-font carried by the front end of said frame, a moistening-roll mounted therein, and a fixedly held strip positioning and severing device disposed between the upper portions of said feed-roll and moistening-roll and having a cutting edge disposed close to the moistening-roll and below the plane of the upper surface thereof. 35
12. In a sealing-strip machine, the combination of a frame, a paper-roll having a shaft journaled in the side members of said frame, bifurcated tension-plates embracing the paper-roll shaft, means for preventing rotation of said plates, nuts having threaded engagement with said shaft and bearing against the tension-plates, a moistening device and a strip-severing device associated with said moistening device. 40
13. In a sealing-strip machine, the combination of a frame comprising side-members having standards at their rear ends and a cross-member connecting said side-members at the lower ends of said standards, a paper-roll journaled in the upper ends of said standards and having a shaft provided with threaded ends, nuts on said shaft, bifurcated tension-plates embracing said shaft and confined between said nuts and paper roll and having their lower ends engaging said cross-member, a feed-roll journaled in said frame, a water-font carried by the front end of the frame, a moistening-roll journaled therein, and a strip positioning and severing device disposed between the upper portions of said feed-roll and said moistening-roll. 45

JOHN BERG.

In presence of—
 JOSEPH SCHWARTZ,
 A. J. FLOYD.
